MERCHANDISE DISPLAY STAND

William S. Leath, Birmingham, Ala., and Jimmie D. Waller, Clinton, S.C., assignors to C. W. Anderson Hosiery Corporation, Clinton, S.C.

Filed Aug. 22, 1969, Ser. No. 18,812

Term of patent 3½ years

Int. Cl. D6—01

U.S. Cl. D80—9

FIG. 1 is a perspective view of a merchandise display stand showing our new design, the side not shown is identical to the side shown and the rear is plain and unornamented;

FIG. 2 is a perspective view of a modified form of the merchandise display stand shown in FIG. 1;

FIG. 3 is a perspective view of a second modified form of the merchandise display stand shown in FIG. 1;

FIG. 4 is a perspective view of a third modified form of the merchandise display stand shown in FIG. 1; and

FIG. 5 is a perspective view of a fourth modified form of the merchandise display stand shown in FIG. 1.

We claim:

The ornamental design for a merchandise display stand, as shown and described.
